UNITED STATES PATENT OFFICE.

ROBERT T. HAZELTON AND LESTER F. NENNINGER, OF CINCINNATI, OHIO.

SPINDLE-STOP MECHANISM.

1,280,024.

Specification of Letters Patent. Patented Sept. 24, 1918.

Application filed December 31, 1915. Serial No. 89,693.

To all whom it may concern:

Be it known that we, ROBERT T. HAZELTON and LESTER F. NENNINGER, citizens of the United States, and residing at Cincinnati, in the county of Hamilton and State of Ohio, have invented a new and Improved Spindle-Stop Mechanism, of which the following specification is a full disclosure.

This invention deals with an improved control-system for an operating mechanical organization, and in its preferred more concrete aspect, it proposes a mechanical system for enhancing the automatic capacities of machine-tools, such as milling-machines, screw-machines, etc.

One object within the contemplation of this invention is to render available a mechanical control-system that may be made use of in various machines to effect a more complete regulation of the automatic operations thereof, as well as more efficiently to enable the various distinctive speeds or the cycle of movements of a given machine-element to be moderated or amplified in duration, and to provide for a wide range of alteration in the timing or sequence of speed-changes and reversals in the cycle.

Another object is to devise an arrangement in the nature of an improvement over the system of the U. S. Patent of Adolph L. De Leeuw No. 1,166,974, issued Jan. 4, 1916, through the provision of mechanical elements arranged to replace and perform the functions of certain electrical features thereof, whereby the table as well as the cutter will come to a stop after all of the pieces bolted thereon have been subjected to the action of the cutter, so that new work may be bolted to the exposed end of the arrested table without liability of injury to the attendant by contact with a rotating cutter. A more specific object in this connection is to provide mechanism whereby the table may be caused rapidly to return to its initial position by merely throwing an appropriate lever, without setting in motion the cutter until the table has completed its return stroke and is ready again to advance.

Another object is to establish a control mechanism based on a simple mechanical system affording the attendant a wide range of adjustability; enabling him in the simplest possible manner, and without drawing upon a high order of skill or of understanding, to set the mechanism for automatically performing such more or less complex actions as may be best adapted for accomplishing a given amount of useful work in the shortest aggregate time.

Another object is to reduce to simpler proportions certain speed-change elements heretofore required, by rendering available a simple scheme whereby a change-gear may, by merely being transposed, be connected with a different driving-element and whereby a pair of such gears may be brought into reciprocal relation with the transmission in which they are embodied.

Another object is to provide a system of transmission providing a plurality of terminal-elements so related to the main source of power and to clutch elements as to enable a wide variety of speed ratios and directions of movement to be obtained by means of comparatively few mechanical parts, such as gears, etc.

Another purpose is to provide a simple mechanical speed-box operated by automatic trips to yield a wide diversity of movements to a work-supporting table.

Another object is to provide a mechanical organization in which a work or tool supporting-element may be caused automatically to progress through a predetermined cycle of operations, at times under the actuation of a major driving-train, and at other times being propelled by an auxiliary driving-train; and to do so in such a way as will enable the sequence and duration of such operations to be easily adjusted and determined by the attendant without necessitating complex and costly instrumentalities.

Other objects and advantages will be in part indicated in the following description, and in part rendered apparent in connection with the annexed drawings.

To enable others skilled in the art so fully to apprehend the underlying features thereof that they may embody the same by the numerous modifications contemplated by this invention, drawings depicting a preferred typical construction have been annexed as a part of this disclosure, and in such drawings, like characters of reference denote corresponding parts throughout all of the views, 10 of which:

Figure 1 is a top plan view partly in section showing one embodiment of this invention. Fig. 2 is an enlarged section through line 2-2 of Fig. 1 showing the construction of 15 the means for rendering the spindle-stop operative or inoperative. Fig. 3 is an end elevation of said means and Fig. 4 portrays the form of the spindle-control rod. Fig. 5 is a sectional end elevation of this embodiment as viewed from the rear thereof. Fig. 6 is a diagrammatic lay-out of the change-gears in their relation to the table. Fig. 6^a shows gears A¹ and A² transposed. Fig. 7 is a plan of the change-gears as assembled 25 and related with the trip-mechanism. Fig. 8 is a detail of the trip-element used chiefly for yielding fast and slow movements of the table. Fig. 9 is a detail of the trip-element used primarily for starting and 30 stopping the table, or reversing the table and stopping the spindle. Figs. 10, 11, 12, 13 and 14 diagrammatically illustrate the positions of the parts, causing the table to stop, go rapidly forward, go slowly forward, go 35 rapidly backward and stop, respectively. Fig. 15 is a diagrammatic analysis of the gearing transmission showing the flow of motion from the initial to the final element and illustrating graphically the manner in 40 which the various changes in the direction and speed are obtainable.

Continuing now by way of a more detailed description of the shown exemplification of this invention, it may be preliminarily noted that, in machine-tool operations, considerable time is usually lost in effecting the contact between the tool and the work. The two will, in the first instance be distanced apart, and to save time it is necessary that 45 either the tool or the work, as the case may be, shall be moved to the other as rapidly as is practical, but thereafter it is necessary that the rate of travel shall be reduced to a point corresponding to the requirements of 50 the ensuing tooling operation. In the case of a milling-machine, for example, the work is bolted to a table that travels with relation to a rotary-cutter and either by reason of the number of separate pieces of work, or by 55 reason of the broken or interrupted surface of a given piece of work, the time of tooling could be reduced in the aggregate if the table could be caused to travel faster and slower

at intervals, corresponding with the duration and frequency of the mere traveling and 65 the actual tooling operations. This class of work calls for an intermittent forward propulsion of the table and a quick continuous return, i. e., a forward series of alternating fast-idle travels and slow-working feeds, 70 which series (in the case of a reciprocating table) may be succeeded by a quick return providing a time interval sufficing for the replacement of the work on the table.

In another instance, the milling operation 75 may be practically rhythmic, and the table may reciprocate from one extreme to the other in such a way as to duplicate its cycle of movements during both the forward and the backward swing. As the tooling operation is necessarily of a relatively long duration, the attendant may be enabled to clamp another piece of work to the advancing end of the table, while the piece is being toolled; but to avoid loss of time, it is necessary, 80 when the table reverses its direction of travel, to cause it to travel rapidly during the first half of its stroke (while the tool is returning over the finished piece or through the distance it has just traveled while cutting it) and then the speed of the table must be reduced to the degree required for the tooling operations, since the tool is now about to start cutting the last added piece 85 of work, and so on in succession. It will 90 thus be seen that the travel of the carriage may be resolved into what are really "positioning" movements and also into what are really "feeding" movements. Technically, the tooling movement is known as a "feed" 100 and the positioning or non-tooling movement is termed a "traverse" or a "quick-traverse."

Now this invention proposes an arrangement such that the table, support or carriage 105 for the tool or the work, as the case may be, may be caused to feed, to position, reverse, or to advance or retreat in any sequence or duration of operations desired.

Turning now to the mechanical diagram 110 represented by Fig. 15, it will be observed that a number of terminal-elements (of which four, 1, 2, 3 and 4, are in this example shown) are connected by suitable conventional mechanical parts, such as shafts, 115 gears, or the like to impart to or receive motion from a primary source of power which will be practically typified by a pulley, built-in motor, or the like.

Certain of these terminal-elements, say 120 those numbered 1 and 2, are connected to rotate oppositely to the other terminal-elements 3 and 4, i. e., 1 and 2 are minus ("−") and 3 and 4 are plus ("+") elements. Another terminal 7 is arranged in proximity to 125 terminal 1, and is adapted as through

clutches and gearing to receive motion through either one of the other terminals 2, 3 and 4 so, as may be selected as to be driven at a rate and direction in proportion to the motions of the selected one of the terminals 2, 3 and 4. Here, for example, the connections including the clutch C are such as to effect a reversal in the direction of the motion transmitted thereby so that, 10 when terminal 7 derives motion from terminal 2, terminal 7 will be driven in a direction contrary to terminal 1, but at a comparatively high rate of speed, which, in this instance, is approximately equal to that of terminal 1. Terminal 7, however, may be connected with terminal 6 instead of with terminal 2, and in that event it will be driven in the same direction as terminal 1 but at a materially different rate, which, in 20 this instance, is considerably slower than that of terminal 1. Moreover, terminal 6, by reason of the character of the transmission, may (by reason of the speed-changer B B') be driven at two different slow speeds 25 by motion derived from terminal 3; or it may be driven at two still different slow rates by motion derived from terminal 4. In this instance the gear-ratios are roughly indicated by figures on the diagram with 30 reference to terminal 4, which is taken at unity.

When the clutch C connects terminal 2 with terminal 7, the transmission leading from terminal 8 will yield a fast movement in one direction (say forward) provided the clutch D connects terminal 1 with terminal 8; while the transmission will yield a fast contrary movement (say backward) provided the clutch D connects terminal 7 with terminal 8.

If, however, clutch C is shifted to connect terminal 7 with terminal 6, then the transmission from terminal 8 will yield a slow forward movement when clutch D connects terminal 7 with terminal 8.

Now this invention, furthermore, puts the above outlined diagrammatic system into practical effect in a very simple manner; the transmission from terminal 8 being used to propel a table which in turn automatically oscillates a trip-controlling clutch D thereby automatically yielding alternate fast and slow forward speeds providing another table-actuable trip-controlling clutch C is in the slow-motion position. If this last mentioned trip has moved clutch C into its other position then will the table execute fast forward and fast backward movements when the first mentioned trip is oscillated. 60 The preferred practical embodiment of this invention may now be more specifically described.

This machine embodies a frame-unit E

which, in this instance, is stationary, and which carries the weight of a table X, which here is adapted to reciprocate. One or more frame-units, such as F and G, are adjustably connected with the frame-unit E, and carry frame-units H and I, which are vertically adjustable and carry the spindles Y and Z, which here are arranged in coaxial relation on opposite sides of the reciprocating table. In this way the spindles may be adjusted with relation to the table X.

The prime-mover is here indicated by P and assumes the form of a pulley adapted to be driven by a belt from a counter-shaft, and which is normally free from the spindle Y, but is adapted to be clutched thereto; and it provides a gear forming a part of the transmission conveying motion to the reciprocating table. This transmission, may, of course, assume various forms, but, in this instance, it comprehends (see Fig. 5) a number of spur-gears P¹, P² and P³ leading in series from gear P and actuating a shaft fixed to bevel gear P⁴. These spur-gears are journaled in the frame F which is adjustable along the bed E, and to provide for such motion the gear P³ is splined to the said shaft. A bevel P⁵ meshes with P⁴ and is fast (see Fig. 4) on shaft P⁶, and from this shaft divers branch-line transmissions (see Fig. 6) lead up to the terminal members 1, 2, 3 and 4. Thus, the end of this shaft terminates in a boss provided with a key (see Fig. 6) indicated by 4, and this key or projection acts itself as a terminal-member, and in this instance happens to be in unitary relation with the shaft P⁶. Adjacent this projection is another similar projection indicated by 3, which serves as a slow-speed terminal member, and it derives motion from the shaft P⁶ by a branch line transmission or train of gearing including the part P⁷, which drives the gear P¹⁰, which in turn meshes with a gear P¹¹ driving the pinion P¹² which meshes with the gear P¹³ secured to the terminal 3.

The terminal 1 is in the form of a gear having clutch-teeth; this gear deriving motion from the parts P⁷ through an intermediate gear P⁸, which has a yieldable driving-relation with the part P⁷ made up of a circle of steel balls spring-pressed radially to seat in notches provided by the part P⁷. The terminal 2 is also in the form of a gear which meshes with the gear P⁸ and which has clutch-teeth. The diameters of the various gears constituting these branch-like transmissions are such that terminal 1 has the highest speed; terminal 2 about the same as 1, being slightly less; terminal 3 having but a fraction of the speed of number 1, say about one-tenth as much; and terminal 4 having several times the speed

of terminal 3, say about six times as much. Terminals 3 and 4, as best shown by the diagram (Fig. 15), are used for delivering motion to terminal 6, and, in this instance, the connection between 6 and these terminals provides a reduction in speed involving furthermore a plurality of changes of speed. Thus, starting with the terminal 5, which in structure is similar to terminal 4, 10 the motion flows through a shaft B to a very small pinion-gear cut in said shaft, and which meshes with a comparatively large spur-gear B¹ which, through a yielding connection similar to that already described, 15 drives the terminal 6. This, therefore, forms a transmission which will, of course, reduce the speed of whatever motion may be obtained from terminals 3 and 4.

The gap between 5 and the two terminals 20 3 and 4 is closed by a large spur-gear A¹ meshing with a similar gear A². These two gears constitute a pair which may be mutually interchanged in position so that the motion may be caused to flow either 25 through A² first and then to A¹, or from A² first and then to A¹; depending upon whether the large or the small gear is directly engaged with the terminal 5. In addition to the speed-changes involved by this reciprocal change, either of these gears may be engaged with either the terminals 3 or 4 depending upon whether they are transposed. That is to say, both of these gears A¹ 30 and A² have a key-way a¹ and a² located on one side of the middle plane of the hub of the gear. On the other side is an enlarged bore. Consequently, if the gear A¹ be in the position shown by Fig. 6 the key-way a¹ will interfere with the terminal lug 3, 35 whereas if it be turned around, as shown in the closely adjacent figure (Fig. 6'), it will engage only with the lug 4. By means of this simple arrangement, the user of a machine is enabled to secure four different 40 speeds simply by adjusting the position of these two gears, and in that way gain the practical effect of a far more costly and elaborate speed change device.

The automatic mechanism for shifting 45 these clutch members D and C to determine the character of motion transmitted to the table, comprehends two trip elements D^o and C^o (Fig. 1) which are located adjacent the longitudinal edge of the table and which 50 are adapted to be actuated by dogs adjustable in the upper groove d and the lower groove e shown best by Fig. 5. These trip elements, together with their dogs, may be constructed precisely as disclosed in the 55 United States patents to Adolph L. De Leeuw, Nos. 1,116,031 and 1,130,685, and, therefore, need not be here described in de-

tail. It will suffice to state that the dogs may be set so as to impact the longer pin d¹ (Fig. 8) and the shorter pin d² of the trip element D^o in succession so as to oscillate it from one position to another, and another dog located in the groove e may impact the pin c¹ and shift the other trip member C^o out of the position in which it had previously been set by hand. These three types of dogs are adjustable along the table so that these actions may be timed to take place in any desired sequence.

Arranged within the casing supporting 75 these parts, are two clutch-operating levers, together with certain connecting elements, whereby either one or both of these levers may be shifted by reason of the action of the dogs. This is shown best by Figs. 8 80 and 9. Dealing first with the mechanism for shifting the clutch D so as to yield fast and slow forward movements to the table (assuming the clutch C meshing with the terminal 6), it is noted that the shaft d³ 85 (Fig. 13) carries a part d⁴ having two V-shaped recesses d⁵ and d⁶ (Fig. 7) separated by a spur d⁷. A clutch shifting lever D⁴ is pivoted about the axis 9 and provides a spur d⁸. A spring D⁵ exerts pressure on the lever 90 D⁴ so as to keep the spur d⁸ in engagement with the part d⁴, and these parts are so proportioned that when the spur d⁸ rests in the notch d⁵, the clutch D will engage with the terminal 7, whereas if the spur d⁸ should occupy the other notch d⁶, then will the clutch 95 D interlock with the terminal 1. In the former case, the table will be driven forwardly at a slow rate (Fig. 12), and in the latter case (Fig. 11) at a fast rate forwardly, providing the clutch member C be interlocked with the terminal 6. It is apparent that the dogs may swing the trip element D^o so as to cause the parts to assume either position and that this shifting may be done without shifting 100 the clutch C.

Considering now (Fig. 7) the other trip element C^o, it is noted that the shaft c¹ thereof also carries a part c⁴ providing two notches c⁵ and c⁶ separated by a spur c⁷, and these notches are adapted to receive a spur 110 c⁸ in a second lever C⁴, which is also held by means of a spring C⁵ with its spur seated against the part c⁴. By locking the shaft c¹, it is, therefore, apparent that the clutch 115 member C on shaft C¹ may be interlocked with either the terminals 2 or 6, thereby producing an effect dependent upon the position of the clutch D. Thus, if the clutch D be interlocked with the terminal 7, then will the locking of the clutch C, with the terminal 2, produce a fast backward motion of the table; or a slow forward motion if C be locked with 6. Or also, if D be locked with

1, then the table will have a fast forward motion irrespective of the position of clutch C; and if clutch D be free from both terminals 1 and 7, then will the table stop irrespective of the positions of the clutch C.

The clutch D can be maintained and held in its wholly disconnected position when the parts are in the position shown by Figs. 10 and 14, or in larger detail by Fig. 7. This position is produced by the impact of a dog carried by the table and the operation of which is to cause the shaft c^6 to rotate clockwise so as to shift the spur c^6 into the notch c^5 and, by means of the lost motion strap 10, 15 to turn the shaft d^4 clockwise to an extent only sufficient to cause the spur d^4 to ride part way up the spur d^5 to occupy the position shown by Fig. 7. This will cause the lever D^4 to move the clutch D into its entirely disconnected position, and this position will be maintained by reason of the mutual opposition of the spring C⁵, and D⁵. This will, of course, cause the machine to stop. Now, if the part C be turned 20 manually anti-clockwise, the spur c^6 will be shifted into the notch c^5 and the lever C⁴ will be moved to cause the part C to interlock with the terminal 6. The link 10 will then be permitted to move to ride sufficiently 25 to permit the spur d^4 to drop in the notch d^5 , thus bringing the parts in the position represented by Fig. 11, corresponding to a fast forward traverse of the table.

A dog may then be caused to impact the 30 part D⁶ and turn it clockwise to bring the spur d^6 into the notch d^5 and thus so move the lever D⁴ as to lock the clutch D with the terminal 7; thereby attaining the position shown by Fig. 12 and yielding a slow forward movement, or so-called "feed" of the table. If now, a dog be caused to impact the 35 part C⁶ and move it clockwise so that the spur c^6 will rest in the notch c^5 then will the clutch C be shifted over into engagement 40 with the terminal 2, and the position shown by Fig. 13 will result, and a fast backward movement will occur.

Now, if a dog impacts the part D⁶ and moves it anti-clockwise, then the spur d^6 will 45 slip over the spur d^5 and rest partway down the other side thereof, and the table will come to a stop; the parts being in the position shown by Fig. 14.

As a result of this arrangement a great 50 variety of movements are attainable through the use of a plurality of dogs. Thus, the table may be caused to move automatically in any one of the ways indicated by the following diagram in which the full lines indicate the rapid or non-tooting strokes; the dotted lines indicate the slow or cutting strokes; the arrows indicate the direction of

the movement, and the bends indicate the reversals in movement.

Among the other things achieved by this invention, one of the more important is the instrumentality whereby the spindle is stopped from rotating at the end of the advanced stroke of the table so that, during the return stroke, the operator may not be injured and the work may not be marred by action of the cutter. Also, the arrangement is such that the feed will not be drawn into action unless the spindle is also set in motion. This arrangement comprehends a connection extending from the hand-operable trip element C^o to a clutch which connects and disconnects the spindle from the prime mover. In this case the spindle derives its motion from a shaft 11 (Fig. 1) through the gears 12, 13, 14, 15, 16 and 17 which are housed in a casing 18 which is adjustably bolted to the frame units F and G, respectively, so as to permit a raising and lowering of the spindle supporting unit H. The spindle Y directly carries the gear 17 which is maintained in proper mesh with the gear 16 by means of a link or strap 19 connected with the shaft 20 which is carried by an arm 21 adapted to swing about the axis of a shaft 11. A driving connection between the shaft 11 and the pulley P is established by causing the rockers 22 to swing until sufficient friction occurs between their fingers 23 and the collar 24 to prevent slipping therebetween. This is produced by shifting a circular wedge 25 so that its conical right-hand raceway crowds under the collars on the outer ends of the levers 22 and lifts them in the necessary direction. The conical wedge 25 is splined to the shaft 11, and this housing action may be obtained by manually operating the hand lever 26 which is provided with a fork 27 to shift the part 25.

The way in which the trip element C^o may disconnect this clutch will now be explained. By turning to Fig. 7, it will be perceived that an arm C^o extends from a shaft C^o and terminates in gear teeth, and corresponding teeth K¹ are cut in one side of the push-rod K which extends forwardly and is provided (see Fig. 4) with a narrow notch K² adjacent its forward end, which notch connects the rod K with a pin in the lower end of an arm L¹ depending from a rock shaft L. This shaft also carries an uprising arm L² which engages (Figs. 2 and 5) with a horizontal arm 28 secured to the lower end of the shaft of the control lever 26. When a dog hits the part C^o through this arrangement, the conical clutch, or wedge, 25 will be moved to the left until its conical side 29 comes home against a stationary conical surface 30 whereupon a braking effect will result and the spindle will be stopped quickly. Conversely, by

swinging the hand lever 26 the spindle may again be started and the table may simultaneously be caused to feed through an actuation of the clutch D. It may be observed that the auxiliary spindle Z will have its action controlled by a connection from the shaft L, similar to that used for the spindle Y, and, therefore, a description of this duplicated construction need not be repeated.

For certain uses it may not be desirable to have the spindle stopped automatically whenever the table is reversed, and, therefore, the connection is formed in such a manner that it may easily be rendered inoperative. Thus, the rod K has a flat surface K³ at an angle of ninety degrees to the teeth K¹, and likewise it provides an elongated slot K⁴ adjacent the slot K².

By removing the cover plate normally concealing the arm L¹, access will be had to the end of the shaft K so that it may be turned slightly and the pin on the arm L¹ be caused to occupy the elongated slot K⁴. This will provide sufficient lost motion so that the spindle will not be automatically stopped when the part C^o is actuated by this dog.

Having thus revealed this invention, we claim as new and desire to secure the following combinations of elements, or equivalents thereof, by Letters Patent of the United States:

1. A control-system of the nature disclosed combining a traveling support; a cutter spindle; power-driven means for simultaneously rotating said spindle and slowly feeding said support in a direction transverse to the axis of said cutter-spindle; and a purely mechanical means cooperative at a predetermined station in the travel of said support automatically to disconnect said power-driven means from said spindle and enable the direction of travel of said support to be reversed to return it to its initial position without setting said spindle in motion.

2. A control-system of the nature disclosed combining a traveling support; a spindle; a power-driven means for simultaneously rotating said spindle and slowly feeding said support; a mechanical connection adapted to feed said support rapidly; mechanical means operative at a predetermined station in the travel of said support automatically to disengage said power-driven means from both said spindle and said support, and for then establishing a propelling relation between said mechanical connection and said support whereby said support will return to its initial position while said spindle is idle.

3. A control-system of the nature disclosed combining a traveling support; a revolving

spindle; a power-driven means for actuating both said spindle and said support; a mechanical connection adapted to actuate only said support; and clutch mechanism for disengaging said means from both said spindle and support for enabling said mechanical connection alone to propel said support.

4. A control-system of the nature disclosed combining a rotary cutter spindle; a work support adapted to travel in a direction transverse to the axis of said cutter spindle; power driven means for simultaneously rotating said spindle and slowly advancing said support; mechanical trip mechanism operative mechanically at a predetermined station in the travel of said support to automatically disconnect said power driven means from said spindle to cause it to stop; and means enabling said support to be re-treated while said spindle remains idle.

5. A control-system of the nature disclosed combining a rotary cutter spindle; a work support adapted to travel in a direction transverse to the axis of said cutter spindle; power driven means for simultaneously rotating said spindle and slowly advancing said support; mechanical trip mechanism operative mechanically at a predetermined station in the travel of said support to automatically disconnect said power driven means from said spindle to cause it to stop; and means automatically causing said support to be retreated at a quick traverse rate while said spindle is idle.

35. A control-system of the nature disclosed combining a rotary cutter spindle; a work support adapted to travel in a direction transverse to the axis of said cutter spindle; power driven means for simultaneously rotating said spindle and slowly advancing said support; mechanical trip mechanism operative mechanically at a predetermined station in the travel of said support to automatically disconnect said power driven means from said spindle to cause it to stop; and means adapted to be manually operated to cause said support to return to its initial position while said spindle is idle.

7. A machine tool control combining a work supporting member and also a tool supporting member; a first and a second terminal element; a primary clutch adapted to connect either of said elements in propelling relation with one of said members; a power driven part connected in driving relation with said first element; and a change gear connected through a clutch with said second element.

8. A machine tool control combining a power driven part; a first, a second and a third terminal member each connected to be driven by power derived from said part;

a fourth terminal member; a table propelling mechanism; clutch means for connecting said mechanism with either said first or said second terminal member; and an auxiliary clutch adapted to connect said fourth terminal member with either said second or said third terminal members.

9. A machine tool control combining a power driven part; four terminal members, 1, 2, 3 and 4 operatively connected with said part to rotate different speeds; a fifth terminal member, 5; a speed change mechanism adapted to connect said fifth member at a different speed ratio with either said third or said fourth terminal member; a table propelling mechanism; and means whereby it may be driven by power transmitted through either said first, said second or said fifth terminal member.

10. A machine tool control combining two co-axially arranged members; a transmitting element adapted to be interchanged in position to engage either one or the other of said members; a tool supporting part and a work supporting part; and means for transmitting motion to one of said parts through said transmitting element.

11. A machine tool control combining three co-axially arranged members, one of said members being co-axially transposable so as to be released from the one and engaged with the other element; supports for a tool and for work; and means for utilizing said transposable element in actuating one of said supports.

12. A machine tool combining two concentric members; a first gear transposable in co-axial relation therewith so as to be engaged by either one or the other thereof; a rotatable part spaced away from said members; a second gear in detachable engagement with said part; said two gears being adapted to be interchanged in position; and means for utilizing said gears in propelling a working element of the machine.

13. A machine tool control combining a reciprocating table; a rotatable spindle adapted to support a milling cutter; a prime mover; table propelling mechanism adapted at a predetermined station to disconnect said spindle from said prime mover; and means for rendering said mechanism impotent to effect said disconnection.

14. A machine tool control combining a table; a spindle; means for rotating said spindle; trip mechanism adapted to render said means inoperative at a predetermined station in the travel of the table; and a device adapted to be manipulated by hand to render said means impotent.

15. A machine tool combining a pair of co-axially arranged spindles; an adjacent

table adapted to reciprocate transversely to the axis thereof; mechanism for propelling said table and simultaneously rotating both of said spindles; and a hand operated control adapted to stop the rotation of both of said spindles without disturbing the normal action of said table.

In witness whereof, we hereunto subscribe

our names, as attested by the two subscribing witnesses.

ROBERT T. HAZELTON.
LESTER F. NENNINGER.
